US0D1039878S

(12) **United States Design Patent** (10) **Patent No.:** **US D1,039,878 S**
(45) **Date of Patent:** **** Aug. 27, 2024**

(54) **TABLE**

- (71) Applicant: **Vitra AG**, Birsfelden (CH)
(72) Inventors: **Ronan Bouroullec**, Paris (FR); **Erwan Bouroullec**, Paris (FR)
(73) Assignee: **Vitra AG**, Birsfelden (CH)

(**) Term: **15 Years**

(21) Appl. No.: **29/775,164**

(22) Filed: **Mar. 22, 2021**

(30) **Foreign Application Priority Data**

Sep. 22, 2020 (WO) WIPO97947
